(57) **CLAIM**

The ornamental design for a valve and handle for a hydronic system, as shown and described.

DESCRIPTION

FIG. 1 is a perspective view from below showing our new design;

FIG. 2 is a side view from one side of the valve and handle for a hydronic system shown in FIG. 1;

FIG. 3 is a bottom plan view of the valve and handle for a hydronic system shown in FIG. 1;

FIG. 4 is a top plan view of the valve and handle for a hydronic system shown in FIG. 1;

FIG. 5 is a perspective view from above of the valve and handle for a hydronic system shown in FIG. 1;

FIG. 6 is a front view of the valve and handle for a hydronic system shown in FIG. 1;

FIG. 7 is a side view from the other side of the valve and handle for a hydronic system shown in FIG. 1; and,

FIG. 8 is a rear view of the valve and handle for a hydronic system shown in FIG. 1.
